UNITED STATES PATENT OFFICE.

ARTHUR JEFFERY, OF HAYWARDS HEATH, ENGLAND.

APPARATUS FOR MELTING AND DISTRIBUTING ADHESIVES.

SPECIFICATION forming part of Letters Patent No. 761,301, dated May 31, 1904.

Application filed July 2, 1901. Serial No. 66,934. (No model.)

To all whom it may concern:

Be it known that I, ARTHUR JEFFERY, a subject of the King of England, and a resident of Muster Green, Haywards Heath, Sussex, England, have invented certain new and useful Improvements in Apparatus for Melting and Distributing Adhesives; and I do hereby declare the following is a full and clear description thereof.

10 This invention relates to an improved apparatus for melting and distributing adhesive substances.

The apparatus consists of a rectangular-shaped vessel, in which the material to be melted is placed. This vessel is open at the top, and the bottom is made sloping, flat in shape at one end and semicircular at the other. A series of heating-tubes are located at or near the lower part of the same. The said vessel 15 fits into another vessel sufficiently large to allow a space all around the said vessel and extending to about half the height of the said inner vessel and is so constructed as to form a space all over the lower part of the inner vessel, so that a heating-chamber is provided for the outside of the lower part of the inner vessel as well as through the tubes aforesaid. The heat is provided by any convenient means—as, for instance, the heat of a lamp 20 attached to one end of the outer vessel, the heated air thus generated passing through an opening provided in the outer casing. A portion of this heated air circulates around the lower part of the inner vessel, and the remaining portion goes through the tubes, so that a large amount of heating-surface is by this means provided for the purpose of heating and melting the glue or other similar substance. The opposite end to that to which the 25 lamp is fixed is perforated with holes, and a baffle-plate for the escape of the heated gas is provided, and also a branch or outlet pipe of convenient diameter is provided at the bottom 30 of the outer vessel for the escape of the heated gas. An outlet branch pipe is provided at the lower end of the inner vessel, which leads down into the outlet-pipe of the outer vessel and terminates in a valve so constructed that when moved it controls the flow of melted glue 35 by covering the end of the branch pipe from

the melting-pot or inner vessel. The whole apparatus may be mounted on a carriage with V-edge wheels which may be made to run in the seams of the floors or decks, and thereby guide the apparatus so that the end of the 40 branch outlet may be exactly over the seam to be filled with the substance. The flow of the liquid glue may be regulated by means of a lever and handle attached to the carriage in any convenient manner. The glue or substance to be melted is placed in the inner vessel, as before mentioned, which becomes heated by the gas generated by the lamp, and the melted substance flows down the sides of or through the tubes into the lower part of the 45 vessel and down into the branch pipe, its liquid state being uniformly maintained till it is led into the seams of the floor.

In order that this invention may be readily understood, reference is made to the accompanying drawings, in which—

Figure 1 represents a side elevation of the apparatus. Fig. 2 is a vertical sectional view, partly in elevation. Fig. 3 is a transverse sectional view. Fig. 4 is a horizontal sectional 55 view of a modified form of the melting-pot detached from the machine, and Fig. 5 is a vertical sectional view of the same. Fig. 6 is a vertical sectional detail showing a series of 60 tapering tubes as distinguished from the vertical cylindrical tubes illustrated in Fig. 5.

The same numerals refer to the same parts in the several views, 1 being the melting-pot or rectangular-shaped vessel, which is open at the top 2, and the bottom 3 is preferably made 75 sloping and semicircular. 4 represents tubes running from back to front of the said vessel.

5 is the outer vessel, of a size to allow of air-space at the sides and ends of the vessel for the convenient passing of the heated air 80 or gas through the apparatus.

6 represents vent-holes in the sides and end of the outer vessel 5.

7 represents baffle-plates for regulating the heat.

8 is a branch pipe or semicircular opening for receiving the funnel or chimney of the lamp 9.

10 is the outlet-tube, preferably tapering 95 in diameter, for conveying the melted sub-

100

stance to the outlet-valve 11. When the valve is open, the liquid glue flows out through the tube 10 and into the seams of the floor or deck or where it is desired to be conveyed. The 5 action of the valve 11 is regulated by the wire rod 12, passing through the valve-tube to a pivoted lever 13, which in turn is pivoted to a rod 14, having a handle 15, sliding upon the handle-bar 16, controlled by the operator who 10 is using the apparatus.

The whole apparatus is mounted on a carriage-frame 17, having wheels 18 with tapered peripheries 19, which are placed at an angle for conveniently running in the seams of the 15 deck or floor.

The heated gas generated by the lamp 9 passes partly through the tubes 4 and partly around the vessel and escapes either through the vent-hole 6 or through the outer tube 20, 20 surrounding the delivery-pipe 10. A large amount of heating-surface is by this means provided, effectually heating and melting the glue in the vessel. The glue lies on the tubes 4 and is gradually melted, flowing down the 25 sides of and between the said tubes to the valve 11, the liquid state of the substance treated being uniformly maintained till it reaches the seams of the deck or floor or place to which it is directed.

30 I prefer to have the inclined beveled wheels 18 upon one side of the apparatus only. The opposite wheels 21 are vertically arranged. The object of inclining the wheels 18 is to permit the machine to be run very close to any 35 raised portion of the deck or next to a vertical wall without coming in contact therewith.

In the modification shown in Figs. 4 and 5 the melted glue flows through the vertical tubes 22 instead of around the same, as in 40 Figs. 1 and 3, the products of combustion passing between the horizontal walls 23 and 24.

Fig. 6 is the same construction as Figs. 4 and 5, except that the vertical tubes 25 are tapered instead of being cylindrical.

45 In the modification shown in Figs. 4 and 5 the flame of the lamp 9 is preferably directed against the beveled plate 26 and some of the vertical tubes nearest the flame are omitted at the points 27 in order to more uniformly 50 equalize the temperature and prevent the overheating of the tubes nearest the flame.

When the glue is placed on top of the tubes 4, 22, and 25 and heat applied through the exterior heating-chamber 5, it will be noted 55 that the glue is melted only at the bottom of the vessel 1 and gradually drips down either around or through the tubes into the delivery-tube 10 and through the valve 11. A portion of the heat is deflected downwardly through 60 the tubular casing 20, keeping the discharge-spout and the valve at a sufficiently high temperature to maintain the glue in its liquid condition until after it is deposited in the seams of the floor or other points.

65 This apparatus for applying glue is highly

desirable, for the reason that there is always a charge or magazine of unmelted glue which is automatically fed to the liquidation-point in the furnace, as required, without further attention. At the same time the fluidity of 70 the glue is maintained through the conveying-pipes and the discharge-valve. After being charged with glue the device is at all times ready for use by simply lighting the lamp, the result being that the glue which 75 had previously cooled in the valve and discharge-pipe and lower end of the furnace is liquefied and the valve 11 rendered operative without any further attention. By this means 80 the decks and floors may be readily repaired 85 at any time. For keeping the decks of vessels and other floors exposed to the weather in proper condition this apparatus has proved itself to be highly desirable and successful.

What I claim as new, and desire to secure 85 by Letters Patent, is—

1. In a paying apparatus, for floors and decks, the combination of a movable adhesive-containing vessel having a melting-compartment below the same, and provided with means 90 for supporting the solid adhesive above the melting-compartment, means for introducing heat to the melting-compartment and means for delivering the melted adhesive to the floor.

2. In a paying apparatus for floors and 95 decks, the combination of a movable adhesive-containing vessel having a melting-compartment below the same, and provided with a foraminous partition for supporting the solid adhesive above the melting-compartment, 100 means for introducing heat to the melting-compartment, and means for delivering the melted adhesive to the floor.

3. In a paying apparatus, for floors and 105 decks, the combination of a movable adhesive-containing vessel having a melting-compartment below the same, and provided with means for supporting the solid adhesive above the melting-compartment, means for introducing heat under pressure to the melting-compartment, and means for delivering the melted adhesive to the floor.

4. In a paying apparatus for floors and decks, a movable adhesive-containing vessel having a foraminous partition, means for heating 115 the vessel, means for guiding the movable vessel by engaging the apparatus with the seams of the floor, and means for delivering the fluid adhesive to the seams of the floor.

5. In a melting apparatus, the combination 120 of a containing vessel having a downwardly-delivery spout, a furnace inclosing the lower portion of said vessel, means for introducing heat to the furnace, an exit-flue from the furnace surrounding the delivery-spout, and 125 means for opening and closing said spout.

6. In a melting apparatus, the combination 130 of a containing vessel having a downwardly-delivery spout, means for guiding the apparatus by engaging the seams of the floor, a

furnace inclosing the lower portion of said vessel, means for introducing heat to the furnace, an exit-flue from the furnace surrounding the delivery-spout, and means for opening and closing said spout.

5. In a melting apparatus, the combination of a wheeled carriage, a containing vessel carried thereon having a downwardly-delivery spout, a furnace inclosing the lower portion of said vessel, means for introducing heat to the furnace, an exit-flue from the furnace surrounding the delivery-spout, and means for opening and closing said spout.

10. In a melting apparatus, the combination of a wheeled carriage, a containing vessel carried thereon having a downwardly-delivery spout, means for guiding the apparatus by engaging the seams of the floor, a furnace inclosing the lower portion of said vessel, means

for introducing heat to the furnace, an exit-flue from the furnace surrounding the delivery-spout, and means for opening and closing said spout.

15. In a melting apparatus, the combination of a wheeled carriage, a furnace and vessel carried thereby, a delivery-spout, and a seam-engaging wheel in line with the delivery-spout.

20. In a paying-machine, the combination of a containing vessel and a furnace therefor, with a delivery-spout and seam-engaging wheel located at the side of the machine.

25. In testimony whereof I have affixed my signature in the presence of two witnesses.

ARTHUR JEFFERY.
